UNITED STATES PATENT OFFICE.

EDWARD J. COLEMAN, OF SCRANTON, PENNSYLVANIA.

SAFETY DEVICE FOR SCREENS.

1,375,828.

Specification of Letters Patent. Patented Apr. 26, 1921.

Application filed September 9, 1920. Serial No. 409,173.

To all whom it may concern:

Be it known that I, EDWARD J. COLEMAN, a citizen of the United States, residing at Scranton, in the county of Lackawanna and

5 State of Pennsylvania, have invented certain new and useful Improvements in Safety Devices for Screens, of which the following is a specification, reference being had to the accompanying drawings.

10 This invention relates to safety devices for screens.

An important object of the invention is to provide a device adapted to prevent screens from becoming accidentally disengaged from 15 their guides and falling from the windows or becoming unfastened from the screen guides.

In the usual construction of rigid screens the screen is provided in its side with a shallow groove adapted to receive the outer face 20 of a strip or track secured to the frame of the window. In order to prevent breaking of the material of the side of the screen, these grooves are generally made very shallow. 25 Consequently, if pressure is applied to the face of the screen the screen becomes disengaged from the guides and falls from the window. An important object of my invention accordingly becomes 30 to provide means whereby the screen may still be supplied with the shallow guiding grooves preventing breakage of the sides thereof but may be so engaged with the guiding strips that it may not be displaced therefrom by pressure in such manner as to 35 fall from the window.

A further object of this invention is to provide a device of this character which may be moved to engaged and disengaged 40 positions and which in the engaged position prevents the removal of the screen and when in the disengaged position permits the removal thereof.

Other objects and advantages of the invention will become apparent throughout 45 the following description.

In the accompanying drawings wherein for the purpose of illustration are shown preferred embodiments of my invention and 50 wherein like reference characters designate like parts throughout:

Figure 1 is a fragmentary side elevation of a screen provided with my safety device.

Fig. 2 is a plan view thereof.

55 Fig. 3 is a section taken on the line 3-3 of Fig. 1.

Fig. 4 is a section taken on the line 4-4 of Fig. 2.

Fig. 5 is a plan view of the screen attached plate. 60

Fig. 6 is an end elevation of the preferred form of my device showing the side flanges employed to prevent transverse displacement of the sliding plate, and

Fig. 7 is a view similar to that shown in 65 Fig. 6, but of the modified form of my device.

Referring now more particularly to the drawings, the numeral 10 indicates a rigid screen provided in the sides thereof with 70 shallow guiding grooves 11 adapted for the reception of the outer face of guiding strips or tracks 12, secured to the casing C of the window proper.

Suitably secured to the upper surface of 75 the screen at the sides thereof are plates 13 having in their outer ends notches 14 conforming to the shape of and alining with the grooves 12 in the sides of the screen 10. These plates have formed therein elongated 80 slots 15 extending longitudinally of the plate and the metal at the sides of the slot is bent upwardly to form upstanding shoulders 16, and at the same time shorten the slots 15. 85

Slidably mounted upon the upper surface of the plates 13 are catches 17. These catches are provided centrally with a longitudinally elongated slot 18. The plate 13 has formed therein an opening O and a 90 headed securing member 19 extends through the elongated slot 18 of the catch 17 and through the opening O of the plate. It will be obvious that the catch 17 is capable of reciprocal motion longitudinally upon 95 the plate 13.

The catch 17 has formed in the end thereof a notch 20 having a depth corresponding approximately to the size of the guiding strips 12 which are usually employed. Extending inwardly from the catches 17 are 100 spring tongues 21, each provided with a foot 22 which engages the upper surface of its respective plate 13 by reason of its inherent resiliency. The spring tongue extends intermediate the shoulders 16 of the plate 13. 105

Suitable means are provided in addition to those already described for preventing transverse displacement of the catch 17 110 upon the plate 13. In the preferred form of my device this means consists in down-

wardly directed flanges 23, which engage the sides of the plate 13 slidably. In the modified form of my device the construction is reversed, the plate 13 being provided 5 with upstanding flanges engaging the sides of the catch 17 as indicated at 24.

In the use of my device as applied to the screen when it is desired to secure the screen against displacement the catch 17 is shifted 10 forwardly so that the notch 20 receives the track 12. When in this position the foot 22 engages in the slot 15 of the plate 13, preventing return of the catch 17 to the withdrawn position due to vibration. It 15 will be noted that the shoulders 16 will protect the spring tongue 21 against crushing if the screen be elevated so that it contacts the upper surface of the window frame. These shoulders likewise prevent accidental 20 engagement of the spring foot 22 in such a manner as to accidentally displace the same from the notch 15 and in addition to the functions above, likewise assist in holding the catch 17 in correctly alined position.

It will be obvious that my device, by reason of the fact that it effectually prevents accidental displacement of the screen at such times as it is desired that such displacement shall be avoided and yet is readily 30 shifted that the screen is released for removal when desired, is particularly well adapted for use, and it will likewise be obvious that the construction as hereinbefore set forth is capable of some change without 35 departing from the spirit of my invention. I accordingly do not limit myself to the specific structure hereinbefore set forth, except as so limited by the subjoined claims:

1. The combination with a screen provided 40 in the side thereof with a shallow groove and a guiding strip slidably engaging in said groove, of a plate secured to the screen provided with a socket, a catch longitudinally mounted upon the upper surface of the plate 45 and provided with a spring foot adapted to engage in said socket, said plate having a notch formed in the outer end thereon of greater depth than the groove formed in the side of the screen.

2. The combination with a screen provided 50 in the side thereof with a guiding groove adapted to slidably receive the outer face of a guiding strip, of a plate secured to the screen and provided with a slot forming a socket, a catch longitudinally shiftably mounted upon said plate and provided

in the end thereof with a notch of greater depth than the groove of the screen, said notch being adapted to likewise receive the guiding strip, flanges extending downwardly from the sides of said catch and engaging the sides of said plate, and a spring foot connected with said catch and adapted to engage in said socket. 60

3. The combination with a window screen 65 provided in the side thereof with a shallow groove adapted for the slidable reception of the outer face of a guiding strip, of a member mounted upon the screen and adapted to be moved into and out of engaged position, said member being provided with a notch of greater depth than the groove of the screen which slidably receives the guiding strip when the member is in the engaged 70 position. 75

4. The combination with a screen provided in the side thereof with a guiding groove adapted to slidably receive the outer face of a guiding strip, of a plate secured to the screen and provided with a slot forming a 80 socket, said plate being provided at the sides of the slot with upstanding shoulders, a catch longitudinally shiftably mounted upon said plate and provided in the end thereof with a notch of greater depth than the 85 groove of said screen and adapted to be moved to engaged and disengaged positions, a spring tongue connected with said catch and extending intermediate the shoulders of said plate, and a foot formed on the end of 90 said tongue, said catch, when in the engaged position, having the notch thereof slidably receiving the guiding strip, said foot when in the engaged position being disposed intermediate said shoulders and being engaged 95 in the socket.

5. The combination with a window screen 100 provided in the side thereof with a shallow groove adapted for the slidable reception of a guiding strip, of a member mounted upon the screen and adapted to be moved into and out of engaged position, said member being provided with a notch of greater depth than the groove of the screen which 105 slidably receives the guiding strip when the member is in engaged position and means resiliently resisting movement of said member when in the engaged position.

In testimony whereof I hereunto affix my signature.

EDWARD J. COLEMAN.
